[57] **CLAIM**

The ornamental design for a dual pruning blade, as shown
and described.

DESCRIPTION

FIG. 1 is a front elevational view of a dual pruning blade
showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof; and,
FIG. 7 is an elevational view showing the pruning blades in
an operative position mounted on a handle member.
The portions illustrated in broken lines in FIGS. 1 and 7 are
for informational purposes only, and are not intended to
form any part of the present design.
